UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-SOLDERING APPARATUS.

Application filed April 23, 1925. Serial No. 25,183.

My invention relates to a soldering apparatus and method and it has for its principal object to provide certain improvements in apparatus for and a method of soldering the type blocks on to the ends of the type bars of typewriting and like machines.

In my prior application, filed September 23, 1918, Serial No. 255,307, now Patent No. 1,587,429 dated June 1, 1926, I have described and claimed an apparatus or fixture for the general purpose stated, and my present improvements are shown applied to a fixture which in most respects is similar to and in some respects identical with the one described in said prior application; but the present improvements are capable of being applied or adapted to apparatus differing specifically from that of my said prior application.

20 To the above and other ends, my invention consists in certain features of construction and combinations and arrangements of parts, and in a certain method, all of which will be fully set forth herein and particularly pointed out in the claims.

One form of my invention is illustrated in the accompanying drawings, in which

Figure 1 is a perspective view of the apparatus as seen from the rear.

30 Figure 2 is a right-hand side elevation partly in central section.

Figure 3 is a right-hand side elevation.

Figure 4 is a detail view on a larger scale and partly in section.

35 Figure 5 is a plan view, partly in section, of the device for holding the type block in place while it is being soldered.

Figure 6 is a view of the same in section on the line 6—6 of Figure 5 and considerably enlarged.

The framework of my apparatus comprises a base casting 1 adapted to rest on a table or work-bench 2 and to project somewhat over the edge thereof as shown, said base 1 being secured to the table by bolts 3 passing through ears 4 of the casting.

50 5 designates the type bar segment of a Remington typewriting machine. This consists of a finished casting having the form of a segment of a circle. Said segment has radial slots 6 sawed in its curved periphery, and in said slots the type bars 7 are journaled on an arc-shaped pivot wire 8, Fig. 2. In the different figures of the drawing some 55 of the slots have not been drawn and only

one or two type bars are shown in place; but this is only for the sake of simplicity in the drawing. In practice the segment when mounted in the fixture as shown is equipped with its full complement of, say, forty-two 60 type bars all assembled.

Means are provided whereby the segment 5 may be readily mounted on the fixture and secured in place in exact position relative to other parts of the fixture. To this end 65 three blocks or posts 10 project upward from the base casting 1, their upper surfaces being trued off with precision. From the two forward ones of these blocks or posts, dowel pins 11, Figs. 2 and 3, project into dowel 70 holes made in the segment 5, said dowel holes being the same ones that are used to locate the segment with precision when it is mounted in the typewriting machine, the framework of which has dowel pins in the 75 same relative positions as the pins 11. The segment is clamped in position by means of two bolts 12, each having at its upper end a projecting arm or finger 13 adapted to be clamped down against the upper surface of 80 the segment 5, one at each end of the chord of the segment. Each of the bolts 12 extends down through a turret-like part 14 of the casting 1, and it has a nut 15 secured on to its lower end, said nut having an arm 85 or handle 16 projecting therefrom. The construction is such that by means of the handle 16 the nut 15 can be loosened and the bolt 12 can then be turned to bring the finger 13 away from the segment 5 so as to 90 allow the latter to be lifted off the dowel pins 11. In practice means are provided whereby the bolt 12 is under the pressure of a spring to lift it and whereby as soon as the handle 16 has turned far enough to relieve 95 the pressure on the finger 13 the bolt automatically turns with the nut so that the whole operation of loosening the clamp consists of one swinging motion of the handle 16, but I have not thought it necessary to 100 illustrate nor fully describe these refinements in the present instance, they being fully described in my prior application above referred to. The drawings do show, however, a pin 17 projecting from the bolt 12 and a stationary pin 18 which serves as a stop for said pin 17 to limit the turning of the bolt in one direction. The construction is such that a segment 5 with its comple- 105 ment of type bars 7 assembled in it can be 110

readily mounted in the fixture and located with precision. After all of the type blocks have been soldered on the type bars the segment can be readily removed to give place to another.

In order to locate each type block with precision relative to the segment 5, a series of matrices 20 are provided each consisting of a rectangular plate, as shown in Figs. 2 10 and 5 with the type characters engraved in its upper surface in intaglio. Each type block 21 has two raised types, one upper case and one lower case character, and there is a matrix for each type block. If the type- 15 writer has forty-two type bars for example, the operator will be equipped with forty- two boxes or compartments, each one containing type-blocks and one of these matrices 20. When a segment is clamped in 20 the fixture, the first matrix is mounted in the fixture as shown and a corresponding type block is set in the engraved matrix which fits it exactly and locates it with precision, and the proper one of the type bars 25 7 is turned down into position as shown in Figs. 1 and 2 in order to have the type block soldered to it.

In order to make the matrices 20 readily attachable and detachable and to locate them 30 with precision, a block 22 is mounted on the top of the casting 1, being located by dowel pins, as shown in Fig. 2, and secured by screws 24, one of which appears in the drawing. Four pins or posts 25, Figs. 2 35 and 5, rising from the block 22, have their upper ends ground off with precision and the matrix plate 20 rests on the tops of these posts. The block 23 has secured to its right-hand edge an upright plate 26 having at its 40 forward and rear ends lugs 27 adapted to act on the right-hand edge of the matrix plate 20 to locate said edge with precision. Another plate 28 has a single lug 30 in position to contact with the rear edge of the 45 matrix plate to locate that with precision. A flat spring 31 secured by screws to the side of the casting 1 is properly bent so as to engage the forward left-hand corner of the matrix plate which is rounded for the 50 purpose and to press said plate against the lugs 27 and 30. As all of these parts are made with great care and accuracy it will be perceived that the type block when set on or in the matrix has its face located with precision with respect to the dowel pins 11, this 55 precision applying in every direction, that is to say, both front and back, right and left, and up and down. The type block is located accurately not only in the respects 60 mentioned but each type is also perfectly level or, in typewriter parlance, "on its feet".

The apparatus is of course so designed 65 that each type when located in the matrix, as described, bears exactly the same relation

to the dowel pins 11 that the printing point of the typewriter does to the corresponding dowel pins in the typewriter framework when printing is to be done with that type. Each of the type blocks is of rectangular 70 outline, as viewed from above in Fig. 5, and has a slot 32 cut lengthwise therein into which the end of the type bar 7 is inserted. This slot is so made as to afford a degree of looseness of the type bar in the slot great 75 enough to allow for the inaccuracies of manufacture of the type bar itself. In other words, if the end of the type bar is not exactly right there is enough extra width in the slot so that said type bar will not disturb 80 the type block, or move it out of the matrix groove. In the soldering operation the extra space in the groove is filled up with solder.

In the Remington typewriter the segment 85 5 has an arc-shaped projection or anvil 33 against which the type bar 7 is intended to strike at about the same instant that the type strikes the paper. It is therefore essential in soldering the type blocks on to the type 90 bars that the face of the type bear a certain definite relation to the plane of this anvil 33. To this end the slot in the type bar is cut deep enough so that when the type bar lies against the anvil, as shown 95 in Fig. 2, its free end does not quite reach to the bottom of the slot. This space beneath the type bar in the slot of course becomes filled with solder. In this way all that is necessary to do in order to get the 100 type face in exactly the right relation to the anvil is to press the type bar down against the anvil during the soldering operation and to hold it there until the solder cools. Any inaccuracy in the free end of the type bar 105 will be compensated for by a variation in the thickness of the layer of solder in the bottom of the slot under the type bar. In Fig. 2 the solder under the type bar is indicated by a heavy black line.

In order more conveniently to apply a flame to the type block to melt the solder the following devices are used as described in my pending application hereinbefore referred to. At the back of the base casting 115 1 an upright bracket 34 is secured by means of screws 35. The upper part of this bracket has two arms 36 only one of which appears in the drawing and in said arms is journaled a rock shaft 37. Between the two 120 arms 36 there is mounted fast on the shaft 37 a structure comprising a hub portion which surrounds said shaft and an arm portion 38 projecting toward the front of the apparatus. As shown in Fig. 1, this arm 125 38 is made in two parallel branches joined near their forward ends by a cross portion 40. The forward end of this arm structure is bifurcated and between the two branches of it a rocking member 41 is piv- 130

oted on pivot screws 42. A metal tube 43 bent into a convenient shape projects upward from the member 41 and is adapted to be connected by a flexible tube 44 with any suitable supply of gas or a mixture of gas and air. The tube 43 communicates through the member 41 with a branched gas tube 45 which has two arms extending one rightward and one leftward, from which arms two gas jets 46 project inward so that when the arm 38 is pulled down to its lowermost position shown in Fig. 2 these two gas jets are directed toward the type block, one playing on each side of said type block. In order to 10 guide the pivoted member 41 so as to bring these gas jets into the right position, said member has an arm 47 projecting upward therefrom and to said arm at 48 is pivoted a guide link 50, which is approximately parallel to the arm 38 and at its rear end is pivoted at 51 to a bracket 52 secured to the main bracket 34. The linkage is so designed that when the arm 38 is down in its operating position shown in Fig. 2 the jets are 20 directed at the type block 21 but when the arm 38 is raised to its position of disuse, shown in Figs. 1 and 3, the piece 45 is inclined rearward so as to carry the flame back to a point where it will not interfere 25 with the operator's manipulation of the apparatus.

In order normally to hold the arm 38 in its upper position, shown in Figs. 1 and 3, the structure 38 is provided with a rearwardly extending arm 53 having projecting from one side thereof a screw 49 to which is connected the upper end of a restoring spring 54, the lower end of which is connected to a pin 55 projecting from the 40 bracket 34.

The downward motion of the piece 38 is limited by a lug 56 projecting from the hub thereof in position to be arrested by a stop 57 consisting of the suitably shaped end of a block of metal adjustably secured to the bracket 34 by one or more screws 58. The upward motion of the piece 38 may also be limited by this same lug 56 striking a part of the bracket 34.

50 When the type bar segment 5 is mounted in the fixture as shown, all of the type bars 7 should stand upright as in Fig. 3. To this end an abutment 60 is provided for contact with the heels of the type bars, this abutment in the present instance consisting of a wire or rod bent into the arc of a circle and secured by small screws 61 (Fig. 1) to the base casting 1.

55 The apparatus or fixture as thus far described differs only in some details of construction from that described in my prior application Serial No. 255,307, hereinbefore referred to.

In said prior application a weighted yoke 65 was provided to grasp the right and left-

hand sides of the type block and hold said type block in position in the matrix as firmly as is necessary for the purpose. I show a similar device in the present instance but with improvements which make it more convenient and also better in its operation. As viewed from one end each of the type blocks tapers upward, being wider near the type bearing base than along its opposite edge or face. This slope in its sides makes it easier 75 to grasp said type block with a weighted device such as that now to be described. This device comprises in effect a pair of pinchers including a block 62 slotted in its right and left-hand sides for the reception 80 of two jaws or small bars of sheet metal, one, 63, being rigidly secured to the block by two pins 64, and the other, 65, being pivoted in its slot by a single pin 66. A compression spring 67 retained in place by two pins 68, tends to cause the rounded ends 70 of the bars 63 and 65 to be pressed together against the opposite faces of the type block. Finger pieces 71 formed on or secured to the forward ends of the bars 63, 65 serve as 90 means for opening the pinchers. The pinchers, when in use extends generally horizontally forward from type block 21.

The block 62 has two brackets 72 and 95 73 secured to its under side by screws 59 and a block 74 has a forwardly directed knife edge 75 and a rearwardly directed knife edge 76 projecting from it through suitable holes in the brackets 72 and 73. A wire 77 secured in the block 74 hangs vertically downward from it and is thence bent rearward underneath the frame 1, and at its lower and rear end has a weight 78 suspended therefrom by what amounts to a universal joint. When the pinchers are in 100 use and grasping a type block, as shown in the drawings, this weight will of course hang a little to the rear of the type block so that the whole structure will be balanced. It will be perceived that the ends of the 105 bars or jaws 63 and 65 being rounded where they contact with the type block 21, will enable a relative oscillation of the weight 78 and the type block 21 in a front and back direction, these rounded contact points pivoting on the type block so that the latter can settle properly into the matrix. As the type block is of an appreciable length in front and back direction, the friction of this rounded connection will not be sufficient to 110 cause the type block itself to rock if the weight should oscillate slightly.

In the right and left-hand direction the type block is much narrower, and a finer joint is desirable, and this is provided by 125 the knife edges 75 and 76. On account of the relative disposition of the parts, as will be understood, the knife edge 76 faces downward and the knife edge 75, as shown in Fig. 6, faces upward, the two knife edges, 130

however, being approximately in alignment. This gives a very delicate pivot so that a relative rocking of the pinchers and the weight on this knife edge pivot can take place very easily and allow the type block to settle exactly level into the matrix. Of course any other pivotal joint that is sufficiently frictionless can be employed in place of these knife edges. This construction of weight or holding device for holding the type in its matrix is an improvement over that shown in my prior application in several respects. It is, however, not of my invention but is the invention of William A. Schmidt.

The arm 38 may be pulled down from its normal Fig. 3 position to its operating Fig. 2 position by hand, but this is more conveniently done by a foot lever, and such a lever is conventionally shown in Fig. 2. This lever 80 is shown as a lever of the first order pivoted in a bracket 81 secured to the floor and having a vertical push rod 82 pivoted to its rear end and extending upward through a hole in the table, and, as shown in Fig. 1, pivoted to an arm 83 which is secured fixedly on one end of the rock shaft 37. The lever 80 is so designed that by pushing it down, as shown in Fig. 2, it depresses the arm 38 until the lug 56 is arrested by the stop 57, at which time the jet is in correct position for heating the solder. This pedal or foot lever is not shown in my prior application. When the pressure of the foot on it is released, the parts are restored to normal position by the spring 54, as has been explained.

I provide a much more convenient and useful means than was shown in my prior application for pressing the type bar 7 which is in the act of being soldered, down against the anvil 33 and holding it there during the soldering operation. As perhaps best shown in Fig. 1, a bracket 84 is secured by screws 85 to the rear side of the main vertical bracket 34 and the upper end of said bracket 84 is made with a long fore and aft vertical slot 86 in which two parallel guide links 87 are pivoted at 88. These links project forward over the hub of the member 38 and at their forward ends a vertical bar or stem 90 is pivoted thereto at 91. This bar 90 is here shown as a long strip of sheet metal doubled back upon itself so as to come down in two branches, the links 87 being pivoted between said branches. At their lower ends these two branches are given a quarter twist so as to embrace between them a curved universal bar 92, which is secured to the bar 90 as by rivets. This universal bar is a strip of metal curved into an arc which is substantially coaxial with the type bar segment 5 and of such extent as to come down on top of whichever type bar is turned to soldering

position. In some of my claims I call this a universal presser bar to distinguish it from the device of my prior application, which was an individual spring device that had to be moved from one type bar to another.

The parallel links 87 guide the universal bar 92 with a parallel motion up and down, its normal position being the elevated inactive position shown in Fig. 3, and its operating position being the depressed position shown in Fig. 2, where it is shown pressing down one of the type bars 7.

In order to operate this universal presser bar 92, one of the links 87 is prolonged rearward to make an arm 93, which, Figs. 2 and 4, lies in the slotted upper end of a vertical rod 94 to which it is pivoted at 95. The rod 94 is comparatively short and is arranged to slide telescopically in a tube or sleeve 96, its motion being guided and limited in extent by a pin 97 extending through the rod 94 and projecting into slots 98 in the tube or sleeve 96. Another vertical rod 100 is rigidly secured in the lower end of the sleeve 96 and a coiled spring 101 is compressed between the rods 100 and 94 so as to press the latter upward. At its lower end, as perhaps most plainly shown in Fig. 1, the rod 100 passes through a horizontal shelf of bracket 102 integral with the bracket 84. This compound structure 94, 96, 100, constitutes a push rod, which, however, is extensible in length by the pressure of the spring 101.

A screw 103 by which the rod 100 is secured to the tube 96 is shaped as shown in Fig. 4 so as to serve conveniently as a means for connecting this compound push rod with a restoring spring 104, which is under tension downward, its lower end being connected to the bracket 102. This screw 103 also serves as a pivot for a link by means of which the compound push rod is operated. This link comprises a piece of sheet metal 105 bent at right angles with one of its flanges pivoted on the screw 103 and to the other of said flanges is secured a wire loop 106, the effect of the whole structure being that the link 105, 106 is a slotted link, the slot being closed at its upper end. In said slot there is adapted to play a headed screw 107 projecting leftward from the arm 53 of the pivoted structure 38.

The parts normally stand in the position shown in Fig. 3 to which position they are drawn by the spring 104, and in which position the lower end of the rod 100 rests on a stop piece 108 which, as here shown, consists of a tongue of sheet metal secured by screws to the bracket 34 and projecting rearward and thence bent into a loop, the whole constituting a sort of yielding stop to arrest the bar 100 when it is restored to the Fig. 3

position by the spring 104, and to do so without undue noise and jar. In this normal position of the parts the screw 107, which is about opposite to the screw 49 in 5 the arm 53, occupies approximately the middle of the long slot in the link 106 and the pin 97 is at the top of the slots 98. When the gas jet is swung down to its operative position shown in Fig. 3, the screw 107 not 10 only moves to the top of the slot in the link 106 but also moves some distance further, pulling upward on said link and pulling the rod 100 and sleeve 96 up to the position shown in Fig. 2. This depresses the universal bar 92 until the latter is arrested by the 15 down-turned type bar, and there is an excess of motion to the rod 100 so that the spring 101 is compressed, as will be apparent from the position in Fig. 2 of the pin 97 20 in the slot 98.

Means are provided whereby when the operator releases the foot lever 80 and allows the arm 38 to rise to the position shown in Fig. 1, the universal presser bar 92 will be 25 held down under the pressure of the spring 101, as shown in Fig. 1. To this end a suitable detent is provided, that shown in the drawing being very simple and convenient. It consists of a rod or bolt 110 slidably 30 mounted in the hollow base casting 1, its front and rear ends passing through holes in said casting and in the bracket 34. This rod has a slot passing through it into which projects the upper end of an arm 111 fastened by means of a set screw 112 on a transverse rock shaft 113 which is journaled in the walls of the base casting 1. One end of said shaft is bent forward to form a handle or finger piece 114. A spring 115, coiled 35 about the shaft 113, tends to project the bolt 110 rearward, its motion in that direction being limited by a stop 116 consisting of the head of a screw screwed into the bolt and adapted to engage the rear wall of the 40 base casting 1, as shown in Fig. 2. The rear end of bolt 110 abuts the rod 100, as shown in Fig. 3, but when this rod is pulled upward by the operation of the pedal 80, said bolt is projected by its spring 115 so that 45 its flattened rear end is beneath the end of the rod 100. When the pedal is released and the parts moved to the position shown in Fig. 1, the lower end of said rod 100 rests on the rear end of the bolt 110 and said 50 rod 100 is thereby prevented from returning to normal position. The parts are so proportioned that when the universal presser bar 92 is resting on a type bar, and the rod 100 is resting on the bolt 110, the pin 97 55 is not quite to the top of the slot 98 and the presser bar is therefore being pressed down against the type bar by the spring 101. The parts remain in this position until the solder has cooled, after which the operator by depressing the finger piece 114 60

withdraws the bolt 110 and allows the spring 104 to restore the bar 92 and the parts connected therewith to the normal position shown in Fig. 3.

The mode of operation of one of these fixtures will no doubt be understood from what has been said. A segment 5, with the set of type bars therein having been mounted in the machine, the operator puts in place the first one of the matrix plates 20, which, by the means described, is located with precision, and places upon the matrix the corresponding type block with the holding device comprising the pinchers and the suspended weight. The first type bar is then turned 70 down, its free end going into the slot in the type block. The pedal 80 is then operated, with the result that the jet is brought down to its operative position shown in Fig. 2, and by the same operation, automatically 75 the universal presser bar 92 is brought down on top of the single type bar that is being soldered. The foot is held on the pedal until the solder has melted. The presser bar is under spring tension, due to the spring 80 101 and it holds the type bar down against the anvil 33. As the bolt 110 has moved under the rod 100 when the pedal is released and the jet is allowed to rise, as shown in Fig. 1, the type bar will continue to be held 85 down by spring pressure as long as the parts are allowed to remain in that position. This will of course be until the solder is cooled 90 sufficiently to permit of raising the type bar and its type block, first striking the finger 95 piece 114 to cause the universal presser bar 100 to be moved out of the way. The second matrix is then put into the machine and the same process repeated with the second type bar.

I find that the process of soldering the type blocks on to the type bars can be very greatly cheapened and also the likelihood of its being done correctly increased by having each operator work two of these fixtures. 105 In practice, two fixtures are placed within reach of each operator, the fixtures being at an angle to one another so that the operator can turn from one to the other. After a segment 110 115 120 125 130 5 is put into each fixture, the operator puts in one fixture, the first matrix and type block, operates the pedal as shown in Fig. 2 until she perceives that the solder is melted, and then releases it, allowing the parts to return to the position shown in Fig. 1 where they are in position to permit of the cooling of the solder. She then turns to the other fixture and does the same thing there. By the time she has carried this second fixture through the same steps of the process, the type block in the first fixture has cooled and she can immediately remove the matrix, substitute a new one and a new type block and bring this second type block to the same stage. At this point she immediately turns

to the second fixture and does the same things, and so on, alternating between the two fixtures. This process has two advantages, one is that the operator loses no time waiting for the type blocks to cool; and the other is that there is no danger of her raising the type bar too soon, that is, before the solder is thoroughly hardened. This there is a strong temptation to do, either from 10 carelessness or from a desire to hurry the work to make a good record or from a desire to make more money in case the work is piece work. In my prior application heretofore referred to, spring means were employed to press the type bar down into the slot in the type block, and hold it down until it cooled. This spring means consisted of a device attachable to the heel of the type bar. An arc-shaped support for it was provided 15 behind the curved set of type bars. When it was necessary to disconnect this device from one type bar and connect it with another, it had to be unhooked from the first and hooked into the second. It will be perceived that using a universal presser bar of the sort that is shown in the present case is far more convenient and much quicker than using the former device. It will also be perceived that this universal presser bar 20 need not necessarily have the precise form shown in the present drawing but that this device is capable of being made in various forms.

It will also be perceived that even if the gas jet were controlled by hand and were not mounted on the rocking device 38, this universal presser bar could be operated by hand or by foot by substantially the same mode of operation as that described. This 25 may perhaps be otherwise expressed by saying that the lever arm 53, which operates this presser bar, need not necessarily in every instance be connected with the gas jet.

It will also be perceived, however, that its 30 automatic operation by means of the gas jet, which would have to be manipulated in any event, is an improvement in several respects. For one thing, it is a distinct saving both of the time and of the attention of the operator. This 35 operation by or in association with the gas jet, has another advantage. It was found that the operators of my former apparatus frequently neglected to apply the spring to the heel of the type bar, either from forgetfulness or from a desire to save time, with the result that some of the type bars did not come down against the anvil and the type block was, therefore, not positioned properly on it. By the present invention, if she solders the type block on at 40 all, she will of necessity bring this presser bar into operation so that there is no chance of its failing to operate through her neglect. Nor is there any danger of her forgetting to raise it because otherwise she could not re-

move the completed type bar out of the way and substitute another one for it.

Various changes may be made in the details of construction and arrangement without departing from my invention.

What I claim as new and desire to secure by Letters Patent is:—

1. The combination with means for holding a type bar support and a type in position for soldering said type to a type bar, 75 of a universal presser bar for pressing the type bar into soldering position and for holding it in position during the cooling of the solder, said presser bar being mounted for motion to pressing position and to inactive position.

2. The combination with means for holding a type bar support and a type in position for soldering said type to a type bar, 85 of a universal presser bar for pressing the type bar into soldering position and for holding it in position during the cooling of the solder, said presser bar being movable to pressing position and to inactive position, said presser bar when moved to pressing position continuing to press against the type bar and when moved to inactive position remaining in that position.

3. The combination with means for holding a type bar support and a type in position for soldering said type to a type bar, 95 of a universal presser bar mounted for motion into and out of position to press the type bar into its soldering position, means to retain said presser bar in its pressing 100 position, and means to restore the presser bar to its inactive position and to hold it there.

4. The combination with means for holding a type bar support and a type in position for soldering said type to a type bar, 105 of a universal presser bar mounted for motion into and out of position to press the type bar into its soldering position, a spring for pressing said presser bar against said 110 type bar, and means to energize said spring and to retain it energized until released.

5. The combination with means for holding a type bar support and a type in position for soldering said type to a type bar, of a 115 universal presser bar mounted for motion into and out of position to press the type bar into its soldering position, a spring, means to energize said spring to press said presser bar against said type bar, a detent for 120 holding said spring energized, and means to release said detent.

6. The combination with means for holding a type bar support and a type in position for soldering said type to a type bar, of 125 means under the control of the operator of the apparatus for applying heat to melt the solder, means under the control of the operator for pressing said type bar into soldering position, the two said means being controlled 130

by a single act of the operator, means acting automatically to continue the pressure against the type bar, and means under the control of the operator for freeing said type bar from such pressure.

7. The combination with means for holding a type bar support and a type in position for soldering said type to a type bar, of means for applying heat to melt the solder, 10 means for applying pressure to the type bar, the two said means being brought into operation by a single act of the operator of the apparatus, means for retaining the pressure against the type bar after the heat applying means has been withdrawn, and means under the control of the operator for removing the pressure.

8. The combination with means for holding a type bar support and a type in position for soldering said type to a type bar, of a gas jet movable to and from position to apply heat to melt the solder, a presser bar movable to pressing position in conjunction with the motion of the gas jet to 25 heating position, said pressing means remaining in pressing position after the jet has been restored to inactive position.

9. The combination with means for holding a type bar support and a type in position for soldering said type to a type bar, of 30 a presser bar mounted for motion into and out of position to press the type bar into its soldering position, two parts having limited relative motion, one of said parts being connected with said presser bar, a spring interposed between said two parts, means for operating the other of said parts so as to move the presser bar to pressing position and to energize said spring, and releasable 40 means for holding said other part.

10. The combination with means for holding a type bar support and a type in position for soldering said type to a type bar, of an arc-shaped universal bar mounted adjacent 45 the set of type bars and movable into and away from a position where it can contact with whichever one of said bars has been brought to soldering position, and means whereby said universal bar may be retained 50 in pressing position independently of the action of the operator.

11. The combination with means for holding a set of type bars and for locating a type block to be soldered, of the universal presser bar 55 92, the parallel links on which it is mounted, the compound operating device comprising rods 94 and 100 and the interposed spring 101, and the detent for said rod 100.

60 12. In soldering apparatus whereby type blocks are soldered to assembled type bars separately moved to place the block-fitting portion of each bar in the block to be soldered to it, a presser bar to the action of 65 which each type bar is subject as the solder

melts and which is mounted on the framework and movable in a single path which intersects the path of movement of each type bar.

13. In soldering apparatus whereby type 70 blocks are soldered to assembled type bars separately moved to place the block-fitting portion of each bar in the block to be soldered to it, the combination of a presser bar to the action of which each type bar is subject as the solder melts and which is mounted on the framework and movable in a single path which intersects the path of movement of each type bar, and bar-retaining means which acts on the presser bar while and after 75 the solder melts and until its action is ended by the operator.

14. In soldering apparatus whereby type 80 blocks are soldered to assembled type bars separately moved to place the block-fitting portion of each bar in the block to be soldered to it, the combination of a presser bar to the action of which each type bar is subject as the solder melts and which is mounted on the framework and movable in a single path which intersects the path of movement of each type bar, heat-applying means 85 mounted on the framework, and devices connecting the presser bar and said means together.

15. In soldering apparatus whereby type 90 blocks are soldered to assembled type bars separately moved to place the block-fitting portion of each bar in the block to be soldered to it, the combination of a presser bar to the action of which each type bar is subject as the solder melts and which is mounted on the framework and movable in a single path which intersects the path of movement of each type bar, heat-applying means 95 mounted on the framework, devices connecting the presser bar and said means together, and bar-retaining means which acts on the presser bar while and after the solder melts and until its action is ended by 100 the operator.

16. The method of soldering types on type 105 bars which consists in mounting two sets of type bars in their supports, accurately positioning a type of one set, turning a type bar into position to be soldered, applying pressure to said type bar, melting the solder, and leaving the pressure applied to said type bar while like steps are being carried out on another type and a type bar of the other set, and so on, alternately, working on a type bar of one set while the solder is cooling in the type bar just operated on in the other set.

17. The combination with means for supporting a type bar segment so that any type bar therein can be turned down in position for soldering a type thereto, of a universal presser bar for pressing any type bar in said segment into soldering position, said presser 115 120 125 130

bar being mounted for motion to pressing position and to inactive position.

18. The combination with means for supporting a type bar segment so that any type bar therein can be turned down in position for soldering a type thereto, of a universal presser bar for pressing any type bar in said segment into soldering position, said presser bar being movable to pressing position

and to inactive position, said presser bar 10 when moved to pressing position continuing to press the type bar and when moved to inactive position remaining in that position.

Signed at the borough of Manhattan, city of New York, in the county of New York, 15 and State of New York this 20th day of April, A. D. 1925.

GEORGE A. SEIB.
